UNITED STATES PATENT OFFICE.

SALVATORE SANTINO, OF CHICAGO, ILLINOIS, ASSIGNOR TO LOUIS C. BERMAN, OF CHICAGO, ILLINOIS.

LIFTING JACK.

Application filed May 3, 1922. Serial No. 558,068.

My invention relates to lifting jacks and has for one of its objects the provision of a simple and efficient lifting jack which can be operated efficiently by unskilled operators.

5 A further object is the provision of a jack of the character mentioned which operates easily and efficiently for both raising and lowering loads.

Other objects will appear hereinafter.

10 Embodiments of my invention are illustrated in the accompanying drawings forming a part of this specification and in which—

15 Figs. 1 and 2 are side elevations of opposite sides of a jack embodying my invention;

Fig. 3 is a section taken on line 3—3 of Fig. 2;

20 Figs. 4 and 5 are vertical sections of the device showing parts in different positions;

Fig. 6 is a rear view of the lower portion of the device;

25 Fig. 7 is an enlarged fragment showing a resilient connecting link used in the construction;

Fig. 8 is a longitudinal section of the same;

30 Fig. 9 is a side view of a jack of slightly different form than that shown in the previous figures;

Fig. 10 is a vertical section of the device shown in Fig. 9; and

Fig. 11 is a view taken on line 11—11 of Fig. 9.

35 Referring more particularly to the drawings, I have indicated a base 12 in which an upright 13 is detachably connected by means of a pin 14. Slidably mounted on the upright 13 is a lower head 15 and an upper head 16.

40 In the upper head 16 is pivoted a lever 17 and the latter carries a cam 18 which is engaged by the upper end of a link 19. The latter is pivoted on a pin 20 in lower member 15. The arrangement is such that when lever 17 is operated in the ordinary stroke in use cam 18 will be rocked from its position shown in Fig. 4 to that shown in Fig. 5, and this rocking of said lever and cam moves the members 15 and 16 from their relative positions shown in Figs. 4 and 5. These movements of the members 15 and 16 effects raising and lowering a weight.

45 In the member 15 is a recess 21 in which is mounted a jaw 22. The form of the jaw

shown is substantially semi-cylindrical with teeth engaging the upright 13, but any desired shape may be given the jaw. In member 16 is a recess having an inclined surface 23 and in said recess is a jaw holder 24 in which is mounted a jaw 25 which may be similar in shape to jaw 22.

50 A spring 26 presses against a portion 27 in member 15 and a short arm 28 on link 19 so as to normally tend to hold the jaw 22 against bar 13. In the upper member 16 is a spring 29 pressing against a portion 30 of said member 16 and the bottom of jaw holder 24 which with the inclined surface 23 and the correspondingly shaped jaw holder 24 tends to hold the jaw 25 against the upright 13.

55 In the raising operation of the device the lever 17 is operated so as to move the cam 18 between the positions shown in Figs. 4 and 5. Owing to the direction of the teeth on jaws 22 and 25 this rocking of the cam makes the members 15 and 16 climb up on the upright 13 and this climbing will raise a weight on surface 31 on member 16.

60 At the top of member 13 is removably attached a jaw 32 which can cooperate with jaw surface 31 when desired or the jaw 32 may support the jack and permit lifting a weight by surface 31 when the jack is suspended on jaw 32. Also the jaw 32 may be inverted and placed in its dotted line position of Fig. 1 so as to raise the effective top surface of member 16 for raising and lowering. Various other uses may be made of the 65 jaw 32 and surface 31 as will be apparent to those skilled in this art.

65 When letting a load down, step by step, the jaws 22 and 25 must be alternatively moved out of contact with upright 13, and to accomplish such movement of jaw 22 I have provided a spring-pressed stop 33 mounted in member 15 with a spring 34 between a suitable shoulder on member 33 and a suitable portion of member 15, as clearly indicated in Figs. 4 and 5. A nut 35 is preferably threaded on the bottom of stop 33 so as to vary the effective height of said stop.

70 The top of stop 33 is adapted to engage a stirrup 36 fixed on a pin 37 which is journaled in member 16. The pin 37 also carries a cam 38 which is adapted to engage an arm 39 on the lower side of jaw holder 24. When the pin 37 is rocked, the stirrup 36 and the cam 38 will be brought into position to op-

erate on stop 33 and arm 39 to alternately move the jaws 22 and 25 away from upright 13. On the outside of the jack is an enlargement 40 on pin 37 with two spaced lugs 41 and 42 on said enlargement. A hand lever 43 is journaled on the pin 37 and has a lug 44 disposed between the lugs 41 and 42. A connecting link comprising a housing 45 is connected to the lever 43 as at 46. In 10 the housing 45 is a rod 47 which is pivoted to a lever 48 on lever 17. A spring 49 is disposed in the housing 45 and a nut 50 is threaded on the rod 47 and presses against a shoulder 51. The arrangement is such that 15 when pressure is used to compress spring 49 the nut can yield away from the part 51, while when pressure is applied in the other direction on rod 47, nut 50 will engage the part 51 and make a rigid connection of the 20 connecting link. The arrangement is such that when hand lever 43 is in its full line position in Figs. 1 and 4, the device will be in condition to lower a weight, and when such lever 43 is in its full line position in 25 Figs. 2 and 5, the device will be in position to raise a load. When the device is in the condition of Figs. 2 and 5, the stirrup 36 will be held out of the path of stop 33, thus permitting the jack to raise a load. When 30 the device is in the condition shown in Figs. 1 and 4, the stirrup 36 will be in position to engage the top of stop 33, when the parts 15 and 16 are brought toward each other and thereby compress spring 34. The tension of 35 spring 34 and the adjustment of nut 35 will be such that when the spring is compressed to a certain degree jaw 22 will be removed from upright 13, thus permitting the member 15 to slide down the rod. When the 40 lever is moved in the opposite direction the tension will be lessened on spring 34 and stop 33, thus permitting jaw 22 to engage the upright 13. When in this condition the cam 38 will engage arm 39 and draw the 45 jaw holder 24 downwardly against the tension of spring 29 and remove jaw 25 from the upright 13, thus permitting the load to be lowered on member 16. When the lever reaches the end of its last-mentioned direction of movement and starts in the other direction both jaws will first be engaged against the upright 13 and then jaw 22 will be drawn away from the upright 13, thus permitting the member 15 to slide down the 50 bar 13 again. This relation of the parts may be repeated to lower the load any distance within the length of the upright 13.

In Figs. 9 to 11, inclusive, a slightly different form of the invention is shown. This 60 form is particularly useful for raising and lowering pleasure automobiles, and the like, and in such an arrangement the bar 13 and upper jaw holder move vertically while the mounting of the lower jaw holder is attached to the base. In this form, the base 55 has a

hollow upright 56 in which is mounted the bar 13. A bearing is provided at 57 and another as at 58 in the housing 59 of the upright part 56. The bar 13 may have a toe 60 for raising a load near the base 55 and when the toe part 60 is provided a slot 61 is formed in one side of the upright 56. Also a guide 62 may be provided for a stop member 63 which is intended to limit the upward movement of bar 13 by engaging the lower 75 jaw holder.

In the housing 59 is an inclined surface 64 against which a jaw holder 65 is mounted. In the jaw holder 65 is a jaw 66 which may be similar in construction to jaws 22 and 25. 80

Slidably mounted on the upright 13 in the housing 59 is a sliding member 67 which has an inclined surface 68 upon which rests a jaw holder 69 and the latter has a jaw 70 therein similar to the jaw 66. A spring 71 85 presses against the top of jaw holder 69 and a suitable portion of member 67. A spring 72 presses against the top of jaw holder 65 and the lower part of member 67.

A lever 73 may be pivoted as at 74 to member 56 and provided with a short lever 75 to which is pivoted a link 76. The latter is pivoted as at 77 to one side of member 67 so that rocking of lever 73 causes vertical movement of member 67, and this movement 90 together with the jaws 66 and 70 and the particular direction of the teeth in such jaws causes raising of a load on the top of bar 13 or on toe 60 of said bar. The bearing 58 is preferably cut away as at 78 to permit arm 63 to pass through such bearing to engage the bottom of jaw holder 65 to limit the upward movement of the upright 13. When the member 63 engages the bottom of jaw 95 holder 65 it prevents the jaw 66 from engaging the bar 13, thereby preventing further upward movement of said bar.

Each of the jaw holders 65 and 69 have upwardly extending arms 79 thereon to which are pivoted levers 80 and 81. Said 100 levers have portions engaging projections 82 and 83 on member 67. Said levers 80 and 81 also have portions which engage the tops of stops 84 and 85. Said stops are mounted in ears 86 on a sliding member 87 and the latter has an arm 88 thereon. Springs 89 are inserted between the enlargements of stops 84 and 85 and the parts 86. Also on the bottoms of stops 84 and 85 are threaded nuts 90 to limit the upward movements of said 105 stops in the ears 86. A pin 91 has a cam 92 thereon which when rocked into the position indicated in Fig. 10 engages the arm 88 and raises the member 87 so as to bring the stops 84 and 85 in the paths of arms of 110 levers 80 and 81. The arrangement is such that when the parts are in the positions indicated in Fig. 10 then oscillation of lever 73 will cause lowering of a load. The 115 springs 89 preferably have considerable 120

more tension than the springs 71 and 72 so that when a load is to be lowered, rocking of lever 73 starting from the positions of Fig. 10 would cause member 67 to be lowered, and since the lever 80 is out of engagement with stop 84 jaw 70 would remain in contact with the upright 13, thereby permitting the bar 13 to carry the load downward. As soon as the member 67 starts downward member 83 would move away from lever 81 and this would cause raising of the jaw holder 65 drawing jaws 66 away from the bar owing to the lever 81 engaging the stop 85. When the lever 73 reaches its terminal of movement stop 85 will permit lever 81 to move jaw holder 65 and jaw 66 downwardly until the latter engages bar 13 to hold the load. Then the movement of lever 73 in the other direction would raise member 67 again, and owing to lever 80 engaging stop 84 jaw 69 would be moved upwardly, drawing jaw 70 away from bar 13, thus permitting the member 67 to be moved upwardly without moving the bar 13 up. When the lever 73 reaches its last-mentioned terminal of movement jaw 66 will be disengaged from the bar, as already mentioned, to begin another cycle of movement for lowering the load again.

30 A thumb lever 93 may be provided on the pin 91 so as to manually move the cam 92 to its full line position on Fig. 10 or to move this cam toward member 87 to permit the latter to drop down so as to render the stops 84 and 85 inoperative with respect to the levers 80 and 81 for use in lowering a load.

I claim:

1. A lifting jack comprising a standard, a pair of slide blocks mounted on said standard, a lever pivoted on one of said slide blocks, a link having one end pivotally connected with said lever and the other end pivotally connected with the other of said slide blocks, a jaw carried by each of said slide blocks for engaging said standard, a spring co-operating with said link and the slide block pivotally connected thereto for moving said last-named slide block relative to said link to hold the jaw thereon in engagement with said standard, a stop movably mounted on said last-named slide block and movable relative to the jaw thereon, a spring interposed between said stop and slide block and operative to exert force on said block tending to release the jaw thereon from said standard, and means on the other of said slide blocks for engaging said stop when said slide blocks approach each other, said engaging means being movable into and out of operative position.

2. A jack comprising an upright member, two blocks slidably mounted on said upright member, jaws carried by said blocks for engaging said upright member, a lever and link operatively connected with said blocks,

a resiliently mounted stop on one of said blocks, said stop being resiliently movable on said block relative to the jaw carried by said block, and a member adjustably mounted on the other block and movable thereon into and out of position to engage said resiliently mounted stop.

3. A jack comprising a bar, two blocks slidably mounted on said bar, a jaw mounted on each of the blocks and engaging said bar, a lever operatively connected with said blocks for moving the latter relatively to each other, a stop movably mounted on one of said blocks, a spring engaging said stop and arranged to be compressed thereby, said stop being movable to compress said spring while said jaw is in holding engagement with said bar, the spring being arranged to release said jaw from said bar when said block is relieved of its load, and a stirrup mounted on the other block and movable thereon into and out of position to engage said stop for compressing said spring.

4. A jack comprising a bar; blocks slidably mounted on said bar; a jaw in one of said blocks; a jaw holder in the other block; a jaw in said jaw holder; a spring engaging said jaw holder and normally holding the last-mentioned jaw against said bar; an arm on said jaw holder; a pin mounted in the last-mentioned block; a movable member fixed on said pin; a resiliently mounted stop in the path of said movable member; and a cam on said pin adapted to engage said arm.

5. A jack comprising a bar; upper and lower blocks slidably mounted on said bar; a lever pivoted to one of said blocks and connected with the other block; a jaw holder in the upper block; a pin journaled in the upper block and having operative connection with said lever; a stirrup fixed on said pin; and a resiliently mounted stop in the lower block in the path of said stirrup.

6. A jack comprising a bar; lower and upper blocks mounted on said bar; a lever pivoted to said upper block and connected with said lower block; a stop slidably mounted in said lower block; a spring between said block and said stop and a portion of the lower block; a nut adjustably mounted on said stop; and a member on the upper block adapted to be engaged by said stop.

7. A jack comprising a bar; upper and lower blocks slidably mounted on said bar; a jaw in the lower block; a jaw holder in the upper block; a jaw in said jaw holder; an arm on said jaw holder; a pin pivoted in the upper block; a stirrup on said pin adapted for movement between said blocks upon oscillation of said pin; and a resiliently mounted stop in the lower block adapted for engagement with said stirrup for disengaging the jaw in the lower block from said bar.

8. A jack comprising a bar; two blocks

slidably mounted on said bar; a lever pivoted to one of said blocks; a link connecting the lever with the lower block; a pin pivoted in the upper block; a jaw holder in the upper block; a cam on said pin adapted to engage said jaw holder for moving the latter relatively away from said bar; an operative connection between the pin and lever; a thumb lever on said pin for rotating the latter respectively of the connection between said pin and lever; a stirrup on the pin adapted for movement between said blocks; and a resilient stop mounted in the lower block.

9. A jack comprising a bar; two blocks slidably mounted on said bar; a lever pivoted to one of the blocks and connected with the other block for moving said blocks relatively to each other on said bar; a pin journaled in one of said blocks; a jaw holder in the last-mentioned block with an arm adjacent said pin; a cam on the pin in the path of said arm; a spring in the last-mentioned block engaging said jaw holder; a thumb lever pivoted on said pin; a connection between the thumb lever and first-mentioned lever; an enlargement on said pin having two spaced stops thereon; a stop on the thumb lever between the stops on said enlargement; a stirrup on said pin adapted for movement between said blocks; and a resilient stop in the lower block extending toward said stirrup.

10. A jack comprising a bar; two blocks slidably mounted on said bar; a lever pivoted to one of the blocks; a rod pivoted to said lever; a pin journaled in one of said blocks;

a thumb lever pivoted on said pin; a housing pivoted on said thumb lever; a rod having pivotal connection with said first-mentioned lever and extending into said housing; and a spring in the housing between a portion of the latter and a stop on said rod.

11. A jack comprising a bar; upper and lower blocks on said bar; a lever pivoted to the upper block; a link pivoted to said lever and the lower block; a pin mounted in the upper block; a thumb lever journaled on said pin; a resilient connecting link pivoted at one end eccentrically to the axis of said first-mentioned lever and pivoted at its other end eccentrically to the axis of the thumb lever; two spaced lugs on said pin; a lug on the thumb lever between the lugs on said pin; a cam on said pin; a jaw holder in the upper block adapted to engage said cam; and a stirrup on the pin adapted to engage a stop on the lower member.

12. A jack comprising an upright bar; two blocks slidably mounted on said bar; a lever pivoted on one of the blocks and operatively connected with the other block; a pin journaled in one of the blocks; a lever on the pin; a resilient connecting link between the lever on said pin and the first-mentioned lever; a stirrup on said pin adapted for movement between said blocks; and a resilient stop on one of the blocks adapted for engagement by said stirrup.

In testimony whereof I have signed my name to this specification on this 1st day of May, A. D. 1922.

SALVATORE SANTINO.
